PLIABLE ELECTRICAL FITTING

Frank W. Hudson, Cleveland, Ohio

Application July 6, 1929, Serial No. 376,166

2 Claims. (CL 173—328)

The present invention relates to soft, pliable, resilient, and yieldable socket and plug fittings adapted for use independently or jointly for providing fluid proof unbreakable electrical conductor connections.

More specifically, the invention relates to socket and plug fittings constructed of molded soft rubber and adapted for detachable association therewith of conductor terminals and contact elements, the fittings being provided with pliable and yieldable portions, whereby the fittings are adapted not only for independent use, but for use jointly for providing conductor connectors which are fluid proof and which are immune to damage by impact and rough usage.

The present invention is an improvement over that disclosed in my co-pending application Serial No. 256,362 filed February 23, 1928 (Patent #1,724,592 of August 13, 1929) of which the present application is a continuation in part.

An object of the present invention is to provide soft, pliable and resilient socket and plug fittings adapted for the detachable association therewith of conductor terminals and contact elements whereby conductor cords of desired lengths can readily be made up and in which the conductors and contact elements are insulated against damage from contact with liquids and are adequately protected from damage due to impacts.

A further object of the present invention is to provide socket and plug fittings, which are formed from soft rubber independently of conductors or contacts and provided with preformed passages and recesses for the detachable reception of the terminals of conductor cords and conductors and contact elements, the passages and recesses being normally substantially smaller than the conductors, conductor cords and contact elements, whereby the latter are firmly and tightly maintained in position by the yieldable reaction of the resilient rubber of said fittings.

A still further object of the present invention is to provide soft rubber socket and plug fittings, adapted for detachable association therewith, of conductors and contact elements whereby conductor cords of any desired lengths can readily be made up for use to suit any particular job in an expeditious manner thus avoiding considerable loss of time usually required in seeking a factory-made fitting having the desired proper conductor cord lengths.

A still further object of the present invention is to provide soft rubber socket and plug fittings

having preformed passages and recesses therein for the detachable reception of electrical cords, conductors and contact elements, the said passages and recesses being so constructed that the walls thereof are expanded in such manner by the insertion of the electrical cords, conductors and contact elements that the reaction of the rubber of said fittings tends to pull said cords, conductors and contact elements into assembled position, and electrically insulate them from each other.

A still further object of the present invention is to provide flexible and yieldable electrical socket and plug fittings adapted for detachable association therewith of conductor terminals and contact elements and adapted for inter-connection in such manner as to provide a detachable connector for electrical conductors, which effectively insulates the conductor terminals and contact elements from contact with fluid and prevents damage to said conductor terminals and contact elements from impacts to which said fittings are subject.

A still further object of the present invention is to provide a flexible and yieldable plug fitting provided with preformed recesses for the detachable reception of contact elements, said contact elements comprising contact fingers mounted for adjustment in the material to fit variously arranged socket plug finger receiving recesses.

A still further object of the invention is to provide a soft rubber plug fitting provided with preformed recesses for the detachable reception of contact elements and fuse members so that said elements and members are insulated from each other by the rubber of the plug.

While socket and plug constructions have heretofore been provided in which the sockets and plugs were composed of soft rubber enlargements or bodies molded onto the ends of electrical conductors and around the contact elements, these constructions do not permit of the detachment of the socket and plug fittings for association with other conductor cord lengths or for repair of parts inasmuch as the parts thereof are molded together in such manner that said bodies have to be taken apart and destroyed in order to gain access to the conductors and contact elements.

Furthermore, conductor cords of this type must necessarily be factory made and when once made up cannot be dis-assembled and the parts thereof used again in order to provide different length cords. In other words, these cords cannot be

made "on the job" to suit the particular requirements at hand.

By providing socket and plug bodies of soft, resilient rubber molded into particular form and shape in accordance with the present invention, I secure all of the advantages of the above noted types of rubber socket and plug devices without any of the above mentioned disadvantages and with many additional advantages.

- 5 5 The rubber socket and plug fittings of this invention are capable of being readily and easily made up into sockets and plugs and joined to conductor cords of various lengths "on the job" to suit the particular requirements of the work 10 and furthermore the socket and plug fittings are of such construction that when assembled with conductor cords and contact elements they can be used under any conditions without damage to the cord terminals or contact elements housed 15 therein, and furthermore the socket and plug fittings in accordance with the present invention are of such construction that they can be expeditiously assembled with the terminals of conductor cords of desired lengths and contact 20 elements and interlocked to provide conductor cord connectors, in such manner that the connectors can be pulled through water, oil, etc. or subjected to impacts without affecting the cord 25 terminals or contact elements which are housed 30 within the socket and plug fittings which fittings provide a socket chamber for the contact elements as well as a yieldable cushion support therefor.

35 With the above mentioned and other objects in view, the invention consists in the novel constructions and combinations of parts hereinafter described, illustrated in the accompanying drawings, and set forth in the claims hereto appended, it being understood that various changes in 40 the form, proportion, size and minor details of construction within the scope of the claims may be resorted to without departing from the spirit or sacrificing any of the advantages of the invention.

45 Reference will be had to the accompanying drawings for a detail disclosure of certain specific physical embodiments of my invention, and wherein:

45 In carrying out my invention I provide plug and socket fittings of soft, and yieldable rubber, which fittings are molded in order to provide recesses and passages therein of definite form for permitting the detachable association therewith of contact elements and electrical conductors in an easy and expeditious manner.

50 As indicated in Figure 1 the socket fitting in a preferred embodiment thereof in accordance with my invention comprises a unitary elongated member 11 which is preferably molded from a very high percentage of the purest and toughest rubber available, the rubber having incorporated therein chemically pure elements in order to give it the maximum resistance to abrasion, light, heat, water, acid, oil, gases and extreme low temperatures. In the molding process the rubber is preferably subjected to an exceedingly high pressure for insuring relative solidity and consequently long life.

55 The socket fitting 11 is so formed in the molding thereof as to comprise a body portion 12, a socket portion 13 and a relatively long extension 14. As indicated, body portion 12 is of substantially hemi-spherical formation and is provided with a reinforcing flange 15 at the juncture thereof with the base of socket portion 13. Body portion 12 merges into extension 14 through a knob like strengthening portion 16. Extension 14 is further provided with a reinforcing terminal bead 17.

60 The socket portion 13 is defined by a relatively long skirt 18 provided adjacent the outer end thereof and exteriorly thereof with a locking bead 19.

bead 21, which, with skirt 19, defines a recess 22 adjacent to and inwardly of bead 21.

The skirt 19 is preferably exteriorly cylindrical from its free end to the bead 21 as indicated at 23 and is tapered so as to enlarge in diameter from recess 22 to flange 15 as indicated at 24. The inner wall of the skirt 19 is cylindrical from the outer end of the skirt to an intermediate point as indicated at 26, from which the inner surface 10 or wall of skirt 19 is tapered so as to enlarge in diameter as indicated at 27, to a laterally offset cylindrical wall 28, which, with a portion of wall 27, defines the outer wall of a circular channel 29, the inner wall of which is defined by body 15 portion 12. The skirt 19 at the outer end thereof is provided with an interior flange 31, as well as a second flange 32 spaced inwardly of flange 31, defining a recess 33 therebetween.

The member 11 is provided in the molding 20 thereof with passages 35 and 36 in the body portion 12 thereof which communicate at adjacent ends with the socket defined by skirt 19 and which at their opposite ends communicate with the inner end of a bore 37 formed in extension 14 in the 25 molding thereof, the bore 37 opening through the free end of extension 14.

The passage 35 opens into the socket space through body portion 12 centrally thereof and is provided with successively enlarged portions 39 30 and 41 adjacent the socket end thereof. Passage 36 opens into the socket space closely adjacent channel 29 substantially diametrically opposite an interruption in the channel defined by the inner wall of skirt 19 merging directly into 35 the outer horizontal wall of body portion 12 for a slight circumferential extent as clearly indicated in Figure 4 and represented at 42.

The inner end of bore 37 is enlarged in the form of a frusto-conical portion 43 with the 40 base thereof disposed inwardly and into which passages 35 and 36 open. As clearly indicated in Figure 1 the inner or base end of portion 43 is disposed inwardly of the junction between body 12 and portion 16 for a purpose later described, 45 and extension 14 is tapered from portion 16 to the terminal bead 11 thereof for providing gradually increasing flexibility from the base to the free end thereof.

The socket fitting 11 as hereinabove described 50 and as illustrated in Figure 1 is adapted to have electrical contact elements and conductors removably associated therewith as indicated in Figures 3 and 6 for providing current for a plug, lamp, etc. adapted to be connected therewith.

In providing member 11 with contact elements 55 and conductors, a conductor cable such as that indicated by the character 45 in Figure 3 is cut off squarely adjacent the end thereof leaving the insulated conductors 46 projecting therefrom after 60 which the insulation is stripped from conductors 46 for a substantial distance leaving the insulation thereon for a distance slightly less than the length of passages 35 and 36. One of the conductors 46 is adapted to extend through passage 65 35 and the other conductor 46 is adapted to extend through passage 36. The conductor 46 for passage 35 is provided with a contact member 47, which is, preferably, secured to the end of the conductor before insertion thereof in member 11. The contact member 47, as indicated in Figure 70 70, comprises a body portion 48 provided with a stepped bore 49 centrally thereof and a cap member 51 for detachable threaded engagement with member 48. In assembling contact member 47 75 with the end of conductor 46 the insulated end

of the conductor is inserted in the larger portion of the stepped bore 49 with the bared portion of the conductor extending through the smaller portion of stepped bore 49 after which the end of the bared conductor is bent over and may be soldered, 5 whereupon cap 51 is screwed onto member 48 into clamping engagement with the bent over end of conductor 46.

Cap 51 may be provided with a transverse aperture 52 for the reception of the end of a 10 wire, by means of which and an extension of the other conductor 46, both conductors are pulled into member 11 from the outer end of extension 14 for drawing conductors 46 into the passages 35 and 36 with the members 48 and 51 of contact member 15 47 seated in the successively enlarged portions 39 and 41 of passage 35 respectively and with the bared portion of the other conductor 46 extending outwardly adjacent channel 29 with which channel passage 36 opens by cutting away the 20 comparatively thin wall separating passage 36 and channel 29 for exposing the bared conductor 46 at this point.

The bared portion of conductor 46 in passage 36 is cut off leaving a sufficient length thereof to 25 project outwardly from the base of channel 29 for contacting engagement with an internally threaded cylindrical contact member 53 detachably positioned within the skirt 19 with the base thereof disposed in channel 29, the member 53 30 being provided with a rectangular cutout 54, see Figure 4, at the base thereof for receiving the portion 42 interrupting channel 29 for preventing rotation of member 53 in socket defined by skirt 19. The bared conductor 46 is yieldably maintained in engagement with contact member 53 by means of a split spring ring member 56 which normally seats in one of the depressions between two adjacent rounded threads of member 53 adjacent 35 the base thereof for disposition in channel 29, the 40 conductor 46 being tightly held between member 53 and ring 56 in a substantially flattened condition, as indicated in Figure 4, thus providing a substantially large contact area.

The cylindrical contact member 53 with the 45 ring 56 therein may be inserted after drawing the corresponding conductor 46 into passage 36 or it may well be assembled prior to the introduction of conductors 46 into passages 35 and 36, the bared portion of conductor 46 in this event being extended between member 53 and ring 56 by springing ring 56 away from member 53 by a suitable tool for providing passage therebetween after which the spring 56 is released for firmly gripping the bared conductor 46.

While the center contact 47 has been described as being assembled with the end of the corresponding conductor 46, prior to the introduction thereof into passage 35, it is entirely feasible to seat the portion 48 of member 47 in the enlarged portion 39 of passage 35 prior to the introduction of the conductors whereupon the extended bared portion of the corresponding conductor 46 is extended through the smaller portion of bore 49 and drawn upwards simultaneously with the other conductor 46 until the end of insulated portion of conductor 46 occupies the enlarged portion of bore 49, after which the bared portion of conductor 46 is cut off adjacent the outer end of member 48, and bent over into contact with the outer end thereof after which the cap 51 is threaded onto member 48 into binding engagement with the bent over portion of conductor 46. While the end of conductor 46 may be soldered to member 48 the construction of contact member is such 75

that a good hold and contact is provided by tightly screwing cap 51 onto member 48, thus avoiding any real necessity for soldering operations though such may be employed, if desired.

The socket fitting 11 is adapted for detachable connection with conductors of different constructions but it is preferable to employ rubber encased conductor cords, and it is highly important that the insulated conductors 46 as well as the rubber covering therefor be of substantially greater diameter than passages 35 and 36 and bore 37 respectively, such that upon drawing the conductors into position as above indicated the passages 35 and 36 and bore 37 will be stretched through yielding of the soft rubber of which member 11 is constructed whereby the conductors will be frictionally and snugly engaged by the walls of passages 35 and 36 and bore 37 by the reaction of the rubber tending to assume its normal condition. By providing the enlarged frustoconical portion 43 of bore 37 provision is made for a more uniform divergence of conductors 46 from the cut end of cable 45 thus greatly reducing the tendency to breaking the cables 46 due to sharp bends therein. Furthermore in pulling cable 45 into position in bore 37 the rubber comprising the cover of cable 45 is compressed into the enlarged portion 43 of bore 37 thus greatly reducing the liability of cable 45 being pulled out of bore 37. Due to the base or wider portion of the enlargement 43 being disposed inwardly of the juncture of body 12 and portion 16 the walls of portion 43 will more readily yield adjacent the base or wider portion thereof due to the restricted cross section of member 11 at this point whereby the end of cable 45 disposed in the portion 43 of bore 37 will tend to provide a head which will greatly resist the pulling of cable 45 from bore 37.

The external diameter of cylindrical contact member 53 is substantially equal to the outer diameter of channel 29, whereby upon insertion of the member 53 in the socket defined by skirt 19 the socket is considerably enlarged with a resulting tension in the skirt 19, thus imparting a yieldable reaction on the outer surface of member 53 resulting in a snug fit between the skirt and said member. Due to the diverging wall 27 the direction of the yieldable reaction on member 53 will be slightly toward the base thereof, thus tending to maintain member 53 in position within skirt 19 with the outer end thereof disposed within and in engagement with the inner wall of flange 32.

It will therefore be seen that while the conductors and contact elements can readily be incorporated in the molded fitting 11 with comparative facility, the construction of member 11 is such as to aid substantially in the retention of these members. The reinforcing flange 15 of member 11 is disposed laterally opposite channel 29 thus offering substantial reinforcement at this point.

From the foregoing it will be seen that a soft rubber socket fitting is provided for removably receiving conductors and contact elements and that the fitting is so constructed that the conductors associated therewith will not be subjected to sharp bends tending to break same and that due to the tapered extension 14 the fitting 11 can be moved from one position to another without liability to sharp bends in the cable 45.

The internally threaded contact member 53 is adapted for screw connection therewith of an ordinary socket plug 61, for providing current for various devices or for the attachment of an extension cable by means of a soft rubber contact

equipped plug fitting comprising a part of the present invention and hereinafter described. The member 53 is also adapted for receiving the contact portion 62 of a lamp 63 as indicated in Figure 6, and when using a lamp as indicated in this figure the flanges 31 and 32 yieldably engage the lamp 63 adjacent the contact portion thereof for forming an effective water seal as indicated at 64 in Figure 6, with this construction a partial vacuum may be formed in recess 33 thus providing a tight contact between lamp 63 and skirt 19. The stretching of the rubber further insures a sealing contact with the lamp.

In Figure 13 is illustrated a modified form of cylindrical contact member, which may be substituted for the contact 53 and which comprises a coil spring section 66 with the convolutions thereof in contact and of a length corresponding to that of member 53 for disposition in the socket space defined by skirt 19 with the opposite ends thereof in contact with the base of channel 29 and the inner edge of flange 32.

In the use of this form of contact member channel 29 may be formed continuous and one end of the strand defining the coil spring section 66 turned over to provide a projection 67 adapted to seat in body 12 at the bottom of channel 29 for preventing rotation of member 66.

By the use of a contact member of this construction a spiral groove is provided by the strand defining the member for the reception of a socket plug, lamp, etc. and the strand defines an external spiral projection also which materially assists in holding the member 66 in contact with the inner wall of skirt 19.

In Figure 14 is disclosed a still further modified form of cylindrical contact member corresponding to member 53, and which comprises a pair of half cylindrical sections 68 with the contacting edges thereof provided with tongues and grooves 69 and 71 for interfitting as indicated in Figure 14, the sections 68 at corresponding edges thereof being provided with aligning cut outs for defining a recess 72 for receiving the channel interrupting portion 42 for preventing turning of the contact member.

The contact members constructed in accordance with this embodiment of the invention can readily be stamped out of comparatively heavy metal and the sections thereof assembled in the socket space within skirt 19 the compression of which will hold the interfitting sections in position.

In Figures 16, 17 and 18, are illustrated modified forms of center contact members, which may separately be substituted for contact member 41 illustrated in Figure 3.

The contact member 74 comprises a one piece metallic member embodying cylindrical sections 75 and 76 for engagement in the successively enlarged portions 39 and 41 of passage 35 and a contact head portion 77. The member 74 is provided with a central bore 79 extending therethrough for the reception of the end of the bared conductor 46 which conductor may be inserted in bore 79 after the contact member 74 is positioned in passage 35 and soldered to member 74 at the end thereof, or the member 74 may be assembled with the bared end of conductor 46 and pulled into position through bore 37 and passage 35 by means of a wire attached to member 74 through an aperture therein similar to member 47.

The contact member 81, illustrated in Figure 17, corresponds to member 74 but instead of having a bore extending therethrough is provided with

stepped recesses 82 and 83 for receiving the insulated and bared portions of conductor 46, the end of the bared conductor being inserted in recess 83 after pouring molten solder therein for securing the conductor to the contact member 81. The contact member 81 is, preferably, provided with a transverse aperture 84 for receiving a wire for pulling contact member 81 with the conductor 46 connected therewith into passage 35.

10 The contact member 85 illustrated in Figure 18 comprises a body portion 86 of stepped external configuration for seating engagement in enlarged portions 39 and 41 of passage 35 and is provided with a central bore 87 opening through one end 15 thereof and communicating with a threaded bore 88 of considerably larger diameter opening through the other end of member 85.

In the use of this form of contact member the body portion 86 is pressed into portions 39 and 20 41 of passage 35 prior to the introduction of the conductors 46 and the bared portion of conductor 46 for passage 35 is pulled through bores 87 and 25 88 until the conductor is in position in fitting 11, after which the projecting bared portion is cut off and the end of the conductor bent over in 30 the base of bore 88, after which a contact screw 89 is threaded into bore 88 in firm contact with the end of conductor 46 for holding same in position in contact member 85.

30 This form of contact member avoids soldering operations and facilitates the assembly of the conductors with the fitting 11.

The socket fitting provided with the conductors and contact elements as above described, while 35 being well adapted for attachment therewith of various devices as lamps or socket plugs for attachment of different contact bearing conductors is further well adapted for co-operation with a similarly constructed soft rubber plug fitting for 40 providing a connection between adjacent ends of a pair of cables which will be substantially immune to damage by contact with oil, water etc. and which also will be capable of withstanding rough usage without impairing the efficiency 45 thereof.

The plug fitting 92 is indicated in Figure 2 and comprises an elongated unitary soft and pliable rubber member molded in the same manner as the socket fitting 11 and is of the general configuration of fitting 11, whereby the cost of manufacture is substantially reduced as well as providing a neater electrical connector embodying the socket and plug fittings 11 and 92 when same are substantially symmetrical as illustrated.

55 The plug fitting 92 comprises a body portion 93, a substantially long outwardly tapered extension 94 and a skirt portion 95.

The body portion 93 is similar to body portion 12 of the socket fitting 11 being substantially of 60 hemi-spherical formation and merging into extension 94 through a knob-like portion 96. The skirt portion 95 converges outwardly from body portion 93 and is provided on the free end thereof with a reinforcing and securing bead 97. A channel 98 is provided in body portion 93 adjacent the union of skirt portion 95 therewith, which channel opens into the space within skirt 95 and is disposed so that the inner wall thereof is substantially co-extensive with the inner surface of 65 skirt 95 thus disposing channel 98 outwardly of the space within skirt portion 95 for a purpose later described.

70 The fitting 92 is provided with a reinforcing flange 99, at the junction of body and skirt portions 93 and 95 laterally opposite the channel 98.

The fitting 92 is further provided by suitable cores in the molding thereof with a bore 101 centrally of extension 94 with one end of the bore opening through the free end of extension 94 and the opposite end thereof terminating in a frusto-conical enlargement 102 within the knob-like portion 96. The extension 94 tapers inwardly toward the free end thereof for providing gradually increasing flexibility of said extension from 10 knob-like portion 96 to the free end of extension 94 which is provided with a reinforcing bead 103.

Fitting 92 is further provided during molding thereof with a pair of passages 104 which communicate with enlargement 102 from which they diverge to a point beyond knob-like portion 96, 15 from where they extend in parallel relation and communicate at their opposite ends with the space within skirt portion 95. Each of the passages 104 is provided in the parallel portion thereof with spaced enlargements 105, 106 and 107 of 20 substantially equal diameter with the enlargement 106 opening through body portion 93 for a purpose later referred to.

The plug fitting 92 as disclosed is adapted to have incorporated therewith conductors and contact elements in an easy and expeditious manner 25 which is preferably effected as follows.

An end of a cable or rubber encased conductor 109 (Figure 3) is cut off squarely leaving conductors 111 projecting therefrom, after which the insulation is stripped from the ends of conductors 111 for a distance from the ends thereof so that the insulation remains thereon for a distance substantially equal to the length of passages 104 from enlargement 102 to the opposite 35 end of enlargement 105 in passage 104. The bared ends of conductors 111 are now inserted in recesses 112 of metallic inserts 113 in which recesses molten solder is poured for soldering the ends of conductors 111 therein, the conductors 40 111 being assembled with the inserts 113 so that the ends of the insulated portions thereof fit within enlarged recesses 114 in inserts 113 under considerable compression, the recesses 114 communicating with recesses 112 at adjacent ends thereof 45 and at the opposite ends thereof opening through the ends of inserts 113, where the recesses 114 are provided with flared or diverging walls, as indicated at 115 for preventing sharp bends in 50 conductors 111 and possible injury thereto.

The inserts 113 as indicated in Figure 5 comprise enlarged opposite end portions 117 and 118 integral with an intermediate reduced portion 119, the recesses 112 being disposed in portions 55 118 centrally thereof and the recesses 114 being disposed centrally of enlarged portions 117.

The enlarged portions 118 are formed with spherical bottomed recesses 121 for the reception of balls 122 which are maintained in recesses 121 for universal movement therein by bending or 60 peening the walls of recesses 121 inwardly as indicated in Figure 5.

The balls 122 are preferably formed integrally with cylindrical portions 123 provided with contact fingers 124 which, as in usual practice, are 65 provided adjacent the free ends thereof with small apertures 125.

After having connected the ends of conductors 111 with the inserts 113 in the manner above set forth a wire is selected, the ends thereof secured 70 in apertures 125 with the loop portion thereof disposed within skirt 95 and upon grasping the loop portion of the wire and pulling thereon the contact fingers 124, inserts 113, conductors 111 and cable 109 are drawn into the position indicated in 75

Figure 3 with the portions 117 and 118 of inserts 113 and portions 123 disposed in enlargements 105, 106 and 107 respectively, and with the insulated portions of conductors 111 disposed in the diverging portions of passages 104 and with cable 109 disposed in bore 101 with the outer end thereof tightly compressed in the flared enlargement 102 of bore 101.

The cable and conductors selected for use with the fitting 92 should be of such diameter that upon inserting same in bore 101 and passages 104 the walls thereof will be appreciably expanded whereby the yieldable reaction of the rubber composing fitting 92 will exert substantial pressure on the cable and conductors for aiding in the retention thereof. The inserts 113 and portions 123 are of substantially greater diameter than passages 104 and enlargements 105, 106 and 107 whereby these parts are maintained in position by the reaction of the rubber which is deformed by expanding the walls of passages 104 upon inserting the inserts 113 therein.

From the foregoing it will be seen that a plug fitting is provided adapted for ready incorporation therewith of contact elements and conductors thus providing a ready yieldable plug-in connection for one end of a conductor or cable in which the metallic contact elements and conductor wires are housed in such manner as to be substantially immune to injury by rough usage such as dropping thereof or subjecting same to heavy impacts in any manner.

The plug fitting 92 provided with the conductors and contact elements as disclosed is well adapted for plugging-in with the ordinary socket plug 61 which may be located in various positions such for example in a wall as indicated at 128 in Figure 7.

In using the fitting 92 in this manner the skirt portion 95 is rolled back over the outer surface of body portion 93 as indicated in said figure, the channel 98 greatly facilitating the rolling back of the skirt 95.

The skirt 95 is, as indicated in Figure 2, relatively thin and by the provision of channel 98 the skirt can be rolled back as indicated with substantially little effort. The reinforcing flange 99 resists the rolling back of skirt 95 thus tending to maintain it in normal position as indicated in Figure 2, but, when the skirt is rolled back the reinforcing bead 97 is stretched, and then due to its tending to assume normal position will contract sufficiently around the body of the fitting to hold the skirt in its retracted position, as indicated on the drawings.

While the contact equipped plug fitting 92 is adapted for different uses as above indicated, it is especially adapted for co-operation with the socket fitting 11 for providing a water and oil proof cable connector as illustrated in Figure 3.

As indicated in this figure, the improved soft rubber socket and plug fittings 11 and 92 provided with their respective conductors and contact elements in the manner above described are utilized for providing connections in conductor cables in an expeditious manner, whereby different lengths of cables can be connected to suit any commercial requirements and which connections are water and oil proof and not subject to damage by impact or other rough usage to which devices of this character are usually subjected.

In making a connection as above indicated, and, as illustrated in Figure 3, the socket and plug fittings 11 and 92 are connected with the ends of the cables 45 and 109 and provided with their re-

spective contact elements in the manner above set forth.

An ordinary socket plug 61 is screwed into the cylindrical contact member 53 with the center contact thereof in bearing engagement with contact member 47, as indicated in said figure. In screwing plug 61 into member 53 the plug is turned slightly beyond the position where it just contacts with contact member 47 thus pushing contact member 47 slightly inwardly as indicated in Figure 3 against the yieldable body portion 12 resulting in a yieldable contact between plug 61 and contact member 47 due to the expansive action of the slightly deformed rubber body portion 12.

After positioning plug 61 as indicated the plug fitting 92 is grasped and the skirt portion 95 retracted as indicated in Figure 7 after which the contact fingers 124 are entered into the recesses in plug 61 and the retracted skirt 95 pushed to its open position resulting in the skirt gripping the outer cylindrical surface 23 of skirt 19 of the socket fitting 11 with the reinforcing bead 97 of skirt 95 seated in recess 22 in compressive engagement with bead 21 of skirt 19 of socket fitting 11.

This close interfitting engagement of the skirt portions 19 and 95 of the socket and plug fittings 11 and 92 respectively prevents the ingress of oil, water or other liquids which would seriously affect the functioning of the contact elements, and furthermore, by connecting the fittings in this manner a partial vacuum is created within the skirt portions which materially aids in preventing separation of the skirt portions.

By the provision of the ball and socket connections between the plug inserts 113 and the contact fingers 124, the contact fingers which are as in usual practice flattened members may be turned about their longitudinal axes to different positions as indicated in Figures 8, 9 and 10 in order to fit socket plug recesses which are formed in different angular relations.

As indicated in Figure 8 the fingers 124 are disposed in parallel relation for engagement in similarly arranged recesses in a socket plug.

In Figure 9 the fingers 124 are disposed at right angles to each other for engagement in similarly disposed socket plug recesses, and in Figure 10 the fingers 124 are parallel but in a position at right angles to that indicated in Figure 8.

While the contact fingers 124 have been indicated as two in number in accordance with the usual practice the plug fitting 92 may be formed for association therewith of a single contact finger as indicated in Figure 11 or three contact fingers may be employed as indicated in Figure 12, the number of contact fingers employed depending upon the particular use to which the plugs are to be put.

As some socket plugs are provided with contact finger receiving recesses which are circular instead of flat in cross section, the contact fingers 124 may be formed circular in cross section and split at right angles longitudinally thereof as indicated in Figure 12 for providing yieldable contacting engagement with the plug recess walls.

In accordance with the construction disclosed in Figures 3 and 5, when the ends of conductors 111 are soldered in the inserts 113, it is desirable to pull the inserts 113 and contact fingers 124 through the bore 101 and passages 104 in assembly thereof with the rubber fitting 92. This may be avoided by the use of the construction illustrated in Figure 19 in which the solder connection is eliminated.

In accordance with this embodiment of the invention, inserts 113' are provided each comprising an enlarged end portion 131, provided with a bore 132, for receiving the insulated end of conductor 111, a reduced portion 133 provided with a bore 134 for receiving the bared end of conductor 111 and which at one end thereof communicates with bore 132 and at the opposite end thereof is enlarged and threaded as indicated at 135 for engagement by a screw 136 integral with a ball socket head 137 in which ball 122 is positioned in the manner above described with reference to Figure 5.

In accordance with this construction, the insert 113' may conveniently be positioned in the enlarged portions of passages 104 prior to the introduction of conductors 111 therein, the bared portions of which may be extended up through bores 132 and 134. The bared portions of the conductors 111 should preferably be cut off to terminate adjacent the screw threaded ends of inserts 113' after conductors 111 are in final position. The ends of the bared conductors may then be spread and the finger bearing heads 137 attached by turning screws 136 into threaded bores 134 into binding engagement with the spread ends of conductors 111. In order to attach the heads 137 from within skirt 95 a suitable tool will of course be employed for engaging heads 137.

The complete structure illustrated in Figure 19 may, of course, be assembled through the bore 101 and passages 104 in the same manner as above disclosed with reference to the construction of Figure 5, if such procedure is desired.

The socket fitting 11 or plug fitting 92 may be modified as indicated in Figure 20 in which the extension 14 and knob-like portion 16 are in the form of a handle 141, whereby the socket member may be conveniently carried from place to place particularly when having a lamp associated therewith, the socket member being otherwise of the same construction as the preferred form illustrated in Figure 1.

While the socket member 11 provided with the internally threaded contact member 53 is adapted for use with lamps or any other electrical devices provided with a threaded contact member, it may be desirable to provide a socket fitting with which a lamp cannot be used but which is especially adapted for cooperation with the plug fitting 92 for providing cable connections in the manner illustrated in Figure 3, whereby the socket fitting provided with the conductors and contact elements will always be in readiness for connection with the plug fitting when it is desired to make a connection which otherwise may be used with a lamp thus causing great inconvenience when it is desired to use it for making a cable connection.

A socket fitting for this purpose is illustrated in Figure 21 and it comprises the extension 14 and knob-like portion 16 of substantially the same form and dimensions as the similar portions represented in Figure 1, but in accordance with this modification of the invention the skirt 19 is eliminated and a body portion 142 provided, which includes the body portion 12 represented in Figure 1 and extends outwardly a distance substantially equal in length to that of skirt 19, having an external configuration corresponding to that of skirt 19 thus resulting in the conservation of bead 21 and recess 22 for cooperation with the plug fitting bead 97 in the manner represented in Figure 3. In other words the socket fitting 75 according to this form of the invention is similar

externally to that indicated in Figure 1, but the socket defined by skirt 19 is eliminated.

The socket fitting in accordance with this form of the invention is provided in the molding thereof with a pair of recesses 143 disposed in the body portion 142 in transversely spaced relation and of a length preferably slightly less than the socket in the fitting 11. The fitting is provided with a bore 27 similar to that disclosed in Figure 1, and with passages 144, which, at adjacent ends thereof, communicate with bore 31, from which they diverge and communicate at their opposite ends with recesses 143. The fitting is provided in the base end thereof with apertures 145 which communicate with the corresponding ends of recesses 143.

The recesses 143 are adapted to have removably positioned therein contact elements which may be of any desired form but which as illustrated comprise each a metal strip 146 substantially equal to the length of recess 143 and adapted to engage one side thereof as indicated in Figure 21. Secured to strip 146 by means of a screw 147 is the offset base portion of a yieldable contact member 148 which contact members are adapted to be engaged by the contact fingers 124 carried by the plug fitting 92.

The conductors and contact members are incorporated in the socket fitting in this form of the invention by selecting a cable in the same manner as above disclosed with reference to Figure 3, securing the bared ends of the conductors to the contact elements by means of screws 147 after which the ends of a wire are engaged with the contact elements and by means of which the contact elements and associated conductors are pulled into position in the passages in the socket fitting.

In Figures 22 to 25 inclusive is disclosed a further modified form of the plug fitting which is constructed for the detachable reception of contact elements and fuse members, thus providing a plug construction having a safety factor. As indicated in Figures 22 and 23 the plug fitting 151 is similar in form to plug fitting 92 embodying substantially the same elements but modified to the extent of the contact recesses and conductor passages. According to this form of the invention the body portion 93 of the fitting is provided with recesses 152 for the detachable reception of contact elements 153 embodying inserts 154 provided with threaded recesses for the detachable reception of screws 155 integral with ball socket members 156, in which balls 122 are universally mounted in the manner above disclosed and as indicated in Figures 5 and 19. The body portion 93 is further provided with a pair of recesses 157, in each of which is detachably positioned a conductor terminal securing member 158 embodying a body portion 159 provided with a threaded bore 160 for the reception of the conductor terminal and which terminal is maintained in position by a screw 161. It will therefore be seen that in accordance with this embodiment of the invention, current is supplied to the members 158 from the conductors connected therewith. The members 158 and elements 153 are electrically connected by fuse members 163 of usual construction, see Figure 5, the one recessed end portion 164 of which is respectively secured between inserts 154 and members 158, and the other end between members 158 and screws 161, as clearly indicated in Figures 22 and 23. In order to facilitate the assembly of the fuse members 163 the body portion 93 is slit between recesses 152 and 157 whereby the portions 166

of fuse members 163 may be pushed downwardly through the slits, which slits as clearly indicated in Figures 23 and 24 will, due to the flowing character of the soft rubber, close as indicated at 167 in Figure 24, thus completely insulating the fuse members.

This construction provides a safety plug fitting by the utilization of the fuse members and by the provision of the removable members 163 and screws 161 as well as the slits a fuse member can readily be replaced when necessary.

In Figures 26 and 27 is illustrated a modified form and as at present, a preferred form of ring member for securing the bared conductor 46 in detachable position in engagement with member 53.

In accordance with this embodiment of the invention, a ring member in the form of a relatively thin band 56' is provided. The band 56' is as indicated preferably of a width equal to the depth of channel 29 and is split with the free ends thereof in spaced relation to receive portion 42 therebetween in the same manner as respects ring member 56.

The band 56' is constructed of brass or any other desirable metal and in the assembly of the socket fitting parts the band is inserted within channel 29 with the inner cylindrical surface thereof in firm engagement with the wall of body portion 12 defining the inner wall of channel 29 and with the spaced ends thereof disposed on opposite sides of portion 42.

After positioning band 56' as indicated conductor 46 is drawn inwardly between band 56' and the adjacent wall of body portion 12, after which the bared conductor 46 is cut off a short distance beyond band 56' leaving sufficient length of conductor to extend over the top and outer face of band 56'. The extended portion of conductor 46 is bent outwardly and downwardly over band 56' as indicated, thus making contact with both opposite faces of the band. After disposing band 56' and conductor 46 in the manner described the cylindrical contact member 53 is pushed into position within socket portion 13 whereby the end of conductor 46 on the outer side of band 56' is tightly clamped in position between band 56' and member 53 with the conductor substantially flattened for providing good contact.

The inner end of member 53 is preferably counter-bored as indicated at 53' whereby upon inward movement of member 53 the projecting end of conductor 46 is forced downwardly into contact with the outer wall of band 56'.

By the provision of the band 56' the assembly of conductor 46 and contact member 53 is greatly facilitated and furthermore a much greater contact area is obtained by extending the bared conductor 46 along both sides as well as over one edge of band 56' and between band 56' and member 53 in substantially flattened condition as disclosed.

A further modified form of center contact member is illustrated in Figure 28 which comprises a body portion 48' provided with a central bore 49' extending therethrough. The body portion 48' is provided with a groove 50 parallel with bore 49' and communicating therewith through a slot 50' adjacent the outer end of body portion 48'. The bared end of conductor 46 is drawn through bore 49' and is then bent outwardly through slot 50' and downwardly in groove 50.

After positioning the body portion 48' with the conductor terminal connected therewith a cap

member 51' is driven over body portion 48' which forces the end of conductor 46 tightly in groove 50 which further effects a frictional grip between body portion 48' and cap member 51'.

By the provision of a contact member as disclosed a substantially large surface contact is provided between the terminal of conductor 46 and the body portion 48' and the conductor is secured to the contact member against separation therefrom even under abnormal pulling forces on the conductor. This form of contact member provides not only for the ready attachment of the conductor thereto but provides a solderless connection for the conductor.

From the foregoing disclosure it will be seen that novel socket and plug fittings are provided which are salable as complete units adapted for detachable engagement with conductor cords and contact elements "on the job" whereby conductor cords provided with socket or plug terminals or both as well as conductor cord connectors can readily be provided with any desired length of cord to suit the particular requirements thus eliminating the otherwise lost time and inconvenience occasioned with types of fittings heretofore employed which were formed integral with the cords, and which cords were of given lengths which may not suit the particular circumstances for which a cord is required.

It will furthermore be seen that the socket and plug fittings of the present invention house the conductor terminals and contact elements in a fluid tight manner and due to the soft rubber construction of said fittings the contact elements housed therein are cushioned against damage by impact whereby the fittings are well adapted for use under all circumstances.

While I have disclosed certain specific embodiments of my invention, they are to be considered as illustrative only, and not restrictive, since the scope of the invention is defined by the subjoined claims rather than by the foregoing specific disclosure.

What I claim is:

1. In combination, a terminal fitting of soft and pliable material, a plurality of electrical conductors extending through preformed passages in said material and contact elements for each of said electrical conductors, each of said contact elements being inserted in separated shoulder recesses in said material and insulated from the other thereby, and one of said contact elements comprising a sleeve-like socket member and a split ring to clamp the ends of a conductor to said sleeve-like socket member.

2. An electrical connection comprising male and female terminal bodies formed of soft rubber, contact members mounted in said bodies, the contact members mounted in one of said bodies being adapted for engagement with the contact members mounted in the other of said bodies, said terminal bodies having portions thereof formed for telescopic engagement including a plug portion on said male body and a resilient skirt portion on said female body adapted to grip said plug portion, and means for preventing the separation of said bodies, said means comprising an annular bead on one of said portions, and an annular groove on the other of said portions adapted to engage said annular bead, said bead and groove being held in engagement with each other by the resilient gripping action of said skirt portion.
